Primary Examiner — Wan Laymon*(74) Attorney, Agent, or Firm* — Cozen O'Connor(57) **CLAIM**

The ornamental design for a glow in the dark aquarium, as shown and described.

DESCRIPTION

FIG. 1 is a front, top, perspective view of a glow in the dark aquarium showing my new design.

FIG. 2 is a top plan view of the glow in the dark aquarium illustrated in FIG. 1.

FIG. 3 is a bottom plan view of the glow in the dark aquarium illustrated in FIG. 1.

FIG. 4 is a front elevational view of the glow in the dark aquarium illustrated in FIG. 1.

FIG. 5 is a rear elevational view of the glow in the dark aquarium illustrated in FIG. 1.

FIG. 6 is a left side elevational view of the glow in the dark aquarium illustrated in FIG. 1; and,

FIG. 7 is a right side elevational view of the glow in the dark aquarium illustrated in FIG. 1.

The stippled shading is used to indicate a transparent material having phosphorescence. The parallel diagonal lines are used to indicate a transparent surface.
